CLAIM

We claim the ornamental design for a one button external storage, as shown and described.

DESCRIPTION

FIG. 1 is a perspective front-top-right side view of a one button external storage showing my new design;

FIG. 2 is a front view according to the invention of FIG. 1; FIG. 3 is a rear view of my first embodiment according to the invention of FIG. 1;

FIG. 4 is a rear view of the second embodiment according to the invention of FIG. 1, the only difference in this embodiment being the placement of the cable jacks; FIG. 5 is a right side view according to the invention of FIG. 1;

FIG. 6 is a left side view according to the invention of FIG. 1;

FIG. 7 is a top view according to the invention of FIG. 1; and,

FIG. 8 is a bottom view according to the invention of FIG. 1.
